CLAIM

The ornamental design for an electrophoresis and electrotransfer device as shown and described.

DESCRIPTION

FIG. 1 is a front perspective top view of an electrophoresis and electrotransfer device showing our new design;

FIG. 2 is a front view of FIG. 1;

FIG. 3 is a back view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in the drawings depict portions of the electrophoresis and electrotransfer device that form no part of the claimed design.
